To all whom it may concern:

Be it known that I, JULIUS L. As shown in the drawing, the leading or material feature of the design consists of a polygonal base or receptacle A and a cover B of pyramidal form comprising side plates b.

The cover has a top plate B', from which rise legs C of irregular shape, and D is the representation of a collar-button surmounted upon said legs. Upon top plate B' and at the front thereof a stag's head E is arranged.
